UNITED STATES PATENT OFFICE.

RICHARD J. LEE, OF MARRERO, LOUISIANA.

INTERNAL-COMBUSTION ENGINE.

Application filed October 31, 1927. Serial No. 229,960.

The present invention relates to an internal combustion engine and has for its prime object to provide an engine embodying a rotatable piston in a circular cylinder and a reciprocating piston in a straight cylinder for operating together for the intake, compression, explosion and exhaust of fuel gases for the purpose of moving the pistons to attain a high degree of power, efficiency and reliability.

A still further important object of the invention resides in the provision of an internal combustion engine of this type which is comparatively simple in its construction, and well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an elevation of the engine embodying the features of my invention,

Figure 2 is a vertical section taken transversely therethrough,

Figure 3 is a longitudinal section taken substantially on the line 3—3 of Figure 1,

Figure 4 is a detail sectional perspective showing a fragment of the circular cylinder,

Figure 5 is a detail sectional view taken substantially on the line 5—5 of Figure 2,

Figure 6 is a perspective view of the ring segment,

Figure 7 is a transverse sectional view through the arcuate piston, and

Figure 8 is a perspective view of one of the spoke elements.

Referring to the drawing in detail it will be seen that the numeral 5 denotes a base from which rises a circular cylinder structure 6 formed in two parts bolted together at 7. A pair of bearings 8 are disposed coaxially in respect to the curvature of the circular cylinder structure 6 one to each side thereof and are connected therewith by means of arms 9 radiating outwardly from the bearings 8 and extending inwardly toward the cylinder structure 6 to be cast integrally therewith or otherwise affixed thereto. A shaft 10 is rotatable in the bearings 8. A rotor 11 is keyed to the shaft 10 within the cylinder structure 6. The cylinder structure 6 is jacketed as at

12 for circulation of a cooling fluid and is formed with the cylindrical bore 14 the axis

of which is circular. The cylinder structure 6 is formed with an annular slot 15 on its inner side communicating with the bore 14. The cylinder structure 6 is provided with an exhaust port 16 disposed tangentially to the axis of the shaft 10. A port 17 is provided in the side wall of the cylinder structure 6 communicating with the bore 14. A port 18 is provided in the cylinder structure on the outer side thereof communicating with the port 14. A piston 19 curved longitudinally is movable in the bore 14 and has a connecting rod 20 engaged therewith through a recess 21 therein by means of a wrist pin 22. This connecting rod 20 extends into a recess 23 formed in the rotor 11 and is fixed in said recess 23 as at 24. A rim segment 26 has an inwardly directed extension 27 at one end bolted or otherwise secured to one end of the piston 19 as at 28. The other end of the rim segment 26 has an inwardly directed extension 29. A plurality of spokes S radiate outwardly from the rotor 11 and engage the ring section 26. Each spoke comprises an inner portion 30 having a reduced terminal 31 embedded in a recess 32 in the periphery of the rotor 11 and the other end is provided with a threaded bore 33 for receiving a threaded stem 35 on which is a lock nut 36 so that the length of the spoke may be adjusted. A shoulder 37 is formed on the stem 35 and a reduced end 38 projects therefrom to be embedded in an opening 39 in the ring section 26. These spokes S extend through the slot 15. An arcuate filler 40 is movable in the slot 15 for closing portions thereof to form the extension chamber as will be more apparent as the description proceeds. This filler 40 extends from an intermediate portion of the piston 19 to the spokes S adjacent the extension 29. The extremity of the extension 29 extends into an opening 41 formed in the filler 40. A flat valve 42 is hingedly mounted at one end as at 43 in a pocket or recess 44 formed in the cylinder structure 6 for the purpose of closing the port 18.

A cylinder block 45 is formed with a straight axis cylinder 46 jacketed as at 47, said jacket 47 communicating with the jacket 12 and the outer end of the cylinder 46 is formed with the port 48 registering and communicating with the port 18. The cylinder block 45 is engaged with the cylinder structure 6 by means of bolts 49 or in any other preferred manner. A spark plug 50 is engaged in the outer end of the cylinder 46. A piston 51 is

mounted for reciprocation in the cylinder 46 and has a connecting rod 52 connected therewith and with the crank of a crank shaft 53 which is rotatable in a crank case 54 bolted as at 55 on the inner end of the cylinder block 45. The cylinder block 45 is formed with a passage 56 leading from the crank case to an intermediate portion of the cylinder 46. The block 45 is formed with a port 57 in the side wall thereof leading outwardly from the cylinder 46. An intake manifold 58 leading from a carburetor 59 communicates with the port 57. A gear 61 is keyed on the crank shaft 53 and meshes with an idler gear 62 journaled on a stub shaft 63 projecting from the base 5. A gear 64 is keyed on the shaft 10 and meshes with the idler gear 62. The gears 61, 62 and 64 are of the same size so that the crank shaft 53 rotates in the same direction with and at the same speed with the shaft 10.

The flat valve 42 is limited in swinging away from the port 18 by abutting the filler 40 and shoulders 66 formed in the cylinder bore 14.

It is thought that the details of construction will now be sufficiently understood to follow the operation of the engine. Referring, therefore, to Figure 2 and supposing the piston 51 to be at the top of its stroke and the piston 19 just passed the port 18. When the pistons are so disposed the spark plug 50 is energized to ignite the explosive mixture in the firing chamber of the cylinder 46 so that the gases will expand forcing the piston 51 downwardly and the piston 19 in a counter clockwise direction. When the pistons 19 and 51 reach the positions shown in Figure 2 the gas in the crank case 54 will be under compression so that as the piston 51 moves downwardly a little more this gas will enter the cylinder 46 above the piston forcing the burnt gases into the cylinder 14 behind the moving piston 19. As the piston 51 moves upwardly the piston 19 moves past the exhaust opening 16 causing the extension 19 and the ring section 26 to close the flat valve 42 so that the gas in the cylinder 46 will be compressed further and the exhaust gases in the cylinder 14 will be forced out through the exhaust port 16.

It is thought that the construction, operation and advantages of the invention will now be apparent to those skilled in this art without a more detailed description thereof. It is to be noted that on the compression upper stroke of the piston 41 a suction is set up in the crank case to suck in a new supply of fuel through the port 57 from the intake manifold 58.

The present embodiment of the invention has been disclosed in detail merely by way of example since in actual practice it attains the features of advantage enumerated as desirable in the statement of the invention and the

above description. It will be apparent that changes in the details of construction, and in the combination and arrangement of parts may be resorted to without departing from the spirit or scope of the invention as herein-after claimed or sacrificing any of its advantages.

Having thus described my invention, what I claim as new is:

1. In an internal combustion engine, a cylinder having an axis describing a closed curve, a longitudinally curved piston movable in the cylinder, the inner side of the cylinder being formed with an annular slot, an arcuate filler piece fixed to the piston and movable in the slot, an arcuate band segment having inwardly directed end extensions one of which is fixed to the piston and the other of which is engaged with the filler piece, a second cylinder having a port communicating with a port of the first cylinder, a flat valve in the first cylinder closable over the ports by the band segment and the second mentioned extensions, a piston movable in the second cylinder, means operatively connecting the pistons to cause the simultaneous rotation of the first piston with the reciprocation of the second piston, means to ignite an explosive mixture in the second cylinder to drive both pistons, means cooperable with the second piston and cylinder for admitting the explosive mixture and compressing the same, said first cylinder having an exhaust port, said means operatively connecting the pistons including a rotor, a connecting rod extending through the slot and connected with the first piston and the rotor, and gearing and a crank shaft and connecting rod operatively connecting the rotor with the second piston, spokes radiating from the rotor through the slot and engaged with the band segment.

2. In an internal combustion engine, a cylinder having an axis describing a closed curve, a longitudinally curved piston movable in the cylinder, the inner side of the cylinder being formed with an annular slot, an arcuate filler piece fixed to the piston and movable in the slot, an arcuate band segment having inwardly directed end extensions one of which is fixed to the piston and the other of which is engaged with the filler piece, a second cylinder having a port communicating with a port of the first cylinder, a flat valve in the first cylinder closable over the ports by the band segment and the second mentioned extensions, a piston movable in the second cylinder, means operatively connecting the pistons to cause the simultaneous rotation of the first piston with the reciprocation of the second piston, means to ignite an explosive mixture in the second cylinder to drive both pistons, means cooperable with the second piston and cylinder for admitting the explosive mixture and compressing the

same, said first cylinder having an exhaust port, said means operatively connecting the pistons including a rotor, a connecting rod extending through the slot and connected with the first piston and the rotor, and gearing and a crank shaft and connecting rod operatively connecting the rotor with the

second piston, spokes radiating from the rotor through the slot and engaged with the band segment, each spoke comprising a pair 10 of threadedly engaged sections.

In testimony whereof I affix my signature.

RICHARD J. LEE.
